UNITED STATES PATENT OFFICE.

EDGAR C. SWINDLER, OF TACOMA, WASHINGTON, ASSIGNOR TO FRED RANDOLPH SMITH.

CONCRETE STAIRWAY CONSTRUCTION.

1,369,493.

Specification of Letters Patent. Patented Feb. 22, 1921.

Application filed March 29, 1920. Serial No. 369,676.

To all whom it may concern:

Be it known that I, EDGAR C. SWINDLER, a citizen of the United States, and resident of the city of Tacoma, county of Pierce, and 5 State of Washington, have invented certain new and useful Improvements in Concrete Stairway Construction, of which the following is a specification.

This invention relates to improvements in 10 stairway construction, and more particularly to the construction of stairways wherein in finished slabs of concrete, marble, or other suitable material, are supported upon a plurality of soffit supporting stringers to coöperate with the soffit in forming a mold for 15 receiving a filling of suitable plastic material, such as concrete, to form the body of the stairway.

The principal object of the invention is to 20 provide a stairway of the above character, having treads and risers of an adjustable character which will permit variation in the height or width of the steps without alteration, together with means whereby these 25 parts may be held rigidly and securely in place while receiving the filling therein.

It is also an object of the invention to provide a stairway that is durable and substantial, is fireproof, of attractive and pleasing 30 appearance and which can be constructed at a relatively small expense.

In accomplishing these and other objects of the invention, I have provided the improved details of construction, the preferred 35 forms of which are illustrated in the accompanying drawings, and described in the following specification.

In the drawings:

Figure 1 is a vertical, sectional view of a 40 portion of a stairway constructed according to the present invention, particularly illustrating the tie members for supporting the risers in position for receiving the concrete filler.

Fig. 2 is a horizontal, sectional view of the stairway.

Referring more in detail to the drawings: 45 1, 2 and 3 designate parallel, spaced apart stringers, preferably of wood, which are 50 supported at their lower ends on a landing or floor, as indicated at 4, and extended upwardly therefrom, at the usual or any desired incline. A soffit 5 is supported by these stringers to form the floor or base of a 55 mold for receiving the filling material.

In building stairways of this character, the lower step is formed first and the others formed successively from the first. Ordinarily such stairways are built between walls which form the ends or sides of the mold for 60 the steps and in other cases suitable end forms are provided.

In the present construction, a mold for each step is formed by its riser and tread; the riser being placed in position first, the 65 interior then filled with the plastic filling, and the tread placed in position and embedded in the filler. The steps are formed successively one upon the other, and when completed and the material has set, the supporting soffit and stringers may be removed. 70

Each of the risers 7 is provided centrally and at its ends, or at spaced intervals, according to the spacing of the stringers, with loops 8, which have their ends embedded in 75 or otherwise secured to the slabs so that the loops are exposed on the inner faces thereof, and secured at their inner ends by means of nails or the like, 9, are tie rods 10 provided with hooks 11 at their outer ends which are 80 extended into the loops 8 to hold the risers rigidly and securely in position while the concrete is being poured therein, and later serves as tie members for holding the slabs 85 in place.

Each of the slabs 12 which form the treads of the steps, is supported at its outer longitudinal edge on a riser 7, and at its inner longitudinal edge is supported when the 90 filler is being poured and before it becomes set, upon the upper or head ends of spikes or the like, 13, that are driven vertically into the stringers. Loops 14 are also formed and extended from the under faces of the risers 95 which are embedded in the filler material while the latter is soft, so that later, after it is set, will hold the treads in place.

Each tread has a rounded depending flange, 15, along its forward edge which overlaps its supporting riser and also forms 100 an abutment for effecting proper positioning of the tread.

In arranging the treads and risers to receive the plastic filler, which in most cases would be concrete, it is apparent that the 105 width of each step could be easily adjusted to any desired width by moving the superimposed riser outwardly toward the forward edge of the tread, and placing the nails 10 for securing the tie rods accordingly. To 110

increase the height of the steps beyond the height afforded by the risers, it is only necessary to place shims between the upper edges of the risers and treads, as is indicated 5 at 20 in Fig. 1, which will give the desired height.

It is apparent that a stairway so constructed will be durable, fireproof and of neat and attractive appearance and comprises features of construction which afford 10 variation in the width and rise of steps to a great extent without altering their original dimensions, and an easy and relatively inexpensive construction is provided.

15 What I claim as my invention is:

1. In a stairway of the character described, a plurality of parallel, inclined stringers, a soffit supported by the stringers, spikes driven vertically into the stringers 20 in transverse alinement thereof, riser and tread forming slabs arranged in superimposed relation to form steps in spaced relation to the soffit, said treads being supported at their inner edges on said vertically alined 25 spikes and at their outer ends on said risers, said risers being mounted on the inner edges of said treads, tie rods secured to the said stringers and treads to hold the latter in position while the stairway is being formed, 30 and a plastic material filling the space between the step-forming slabs and soffit.

2. In a stairway of the character described, a plurality of spaced apart, parallel inclined stringers, a soffit supported by said 35 stringers, spikes or the like partly driven into said stringers at spaced intervals in transverse alinement thereof, tread forming

slabs supported in horizontal position at their inner edges by said transversely alined spikes, riser-forming slabs mounted on each 40 of said treads and supporting the outer edges of the tread superimposed thereon, said risers having loops formed therein and extending at the inner faces thereof, tie rods secured in said loops and to said stringers to secure the 45 risers at adjusted positions on the treads, and a plastic material filling the space between the soffit and step-forming slabs, for the purpose set forth.

3. In a stairway of the character described, a plurality of inclined stringers, a soffit supported by the stringers, spikes driven partly into the stringers in alinement transversely thereof, tread forming slabs mounted at their inner edges on said transversely alined spikes and having depending 55 flanges at their outer edges, riser-forming slabs mounted on the inner edge of each of said treads abutting the flange and supporting the outer edges of the next higher tread, 60 hook receiving loops secured to said risers and extending from the inner faces thereof, tie rods having hooks at their outer ends seating in said loops and having anchor members at their inner ends whereby they may be 65 detachably secured to said stringers to hold the risers at adjusted positions on the treads while the stairs are being formed and a plastic material filling the space between the steps and soffit.

Signed at Tacoma, Pierce county, Washington, this 19th day of March, 1920.

EDGAR C. SWINDLER.
